UNITED STATES PATENT OFFICE

ERNST KNÜTTEL, OF KALKBERGE/MARK, GERMANY

CENTRIFUGAL APPARATUS

Application filed February 15, 1928, Serial No. 254,448, and in Germany February 22, 1927.

My invention relates to centrifugal apparatus and more particularly to apparatus for the continuous treatment of liquids containing suspended matter, including pulps, 5 colloids and the like. Centrifugal apparatus of various types have already been proposed for the treatment of such liquids, for instance apparatus having perforated or solid cylindrical, tapering or lenticular 10 bowls. In these apparatus various means are provided for separating the solids from the wall of the bowls, for instance, scrapers, means for displacing the bowls or part of their walls, or slides and valves of other 15 kinds at the periphery of the bowls. However, for solids which are particularly finely subdivided, only unperforated bowls can be employed. A particularly difficult problem 20 is the centrifuging of pulps having suspended therein very finely subdivided solids of exceptional density, as such solids stick very firmly to the walls of the bowl and are difficult to remove by scrapers. The solution 25 of the problem by displacing part of a tapering or lenticular bowl in order to eject the solids is not satisfactory on account of the excessive thrust exerted on the parts controlling the displacing mechanism which may become prohibitive in machines of larger 30 size. Discharging the solids by several slides or valves at the periphery is primitive and unreliable, apart from the fact that hard and sharp solids cause considerable wear of 35 these parts which interferes with the operation of the apparatus.

It is an object of my invention to provide a centrifugal apparatus which is suitable for the treatment of any liquids containing suspended solids, but is particularly designed 40 for liquids containing dense and very fine solids. To this end I provide a bowl having unperforated walls, a peripheral annular discharge slot of invariable width and an annular valve which is adapted to close the 45 slot so that the separated solids act as the packing.

In a preferred embodiment of my invention I so design the annular valve that the solids are collected between the valve and 50 the edges of the bowl.

Advantageously the bowl is of lenticular cross-section and constituted by two sections defining between them a peripheral slot of invariable width, and the annular valve or slide is so designed that the centrifugal action will exert on it a component tending to open the valve in order to facilitate the opening thereof.

I may arrange a plurality of bowls on a common shaft which are operated simultaneously or preferably alternately, by duplicating the annular valve and controlling a pair of bowls alternately by the two valves.

The liquid to be treated may be introduced by means of a stationary tube arranged coaxially within the hollow driving shaft of the apparatus.

In the drawing affixed to this specification and forming part thereof a pair of centrifugal bowls embodying my invention are illustrated diagrammatically by way of example in axial section.

Referring now to the drawing, *a* is a hollow shaft, *b* and *c* are centrifugal bowls keyed on the shaft each comprising an upper section *d* and *d'* and a lower section *e* and *e'*, respectively, the two sections of each bowl defining between them a substantially lenticular annular chamber. Peripheral discharge slots *f* and *f'*, respectively, are constituted by parallel faces or edges *m* and *u* on the parts *d* and *e* and *i'* and *v* on the parts *d'* and *e'*, respectively.

In the parts *d* and *e* constituting the upper bowl *b*, a beveled face *s* is formed adjacent the parallel face *m* of the upper part *d* and a peripheral rib *w* extends downwardly from the beveled part so as to form an annular peripheral recess *h* on the part *d*. Outwardly extending flanges *i* and *x* are formed adjacent the parallel edges *u* and *i'* of the parts *e* and *e'*, respectively, the flange *i* extending downwardly and the flange *x* extending upwardly from the parallel faces *u* and *i'*, respectively. *h'* is a peripheral recess on the lower part *d'* of the bowl *c* which is constituted by an upwardly extending rib *w'* and a short beveled face adjacent to parallel edge *v*.

Means are provided for varying the area 100

through which the goods from the bowls *b*, *c* are discharged after having passed the slots *f*, *f'* and such means comprise an axially displaceable slide *g* which is splined 5 on the shaft between the bowls *b*, *c* so as to partake in the rotation of the shaft but free to be displaced in parallel to its axis as indicated by the arrows. *g'* and *g''* are cups formed at the upper and lower arms of the 10 slide *g* and constitute a duplicate valve for the bowls. The upper cup *g'* is equipped with a peripheral flange *y* extending into the recess *h* of the part *d*, *z* is a beveled face extending downwardly from the flange and 15 *z'* is a recess formed below the beveled face for the reception of the flange *i* on the part *e*. The lower cup *g''* is formed with a downwardly projecting flange *y'*, mating with the recess *h'*, a beveled face *z''* and a recess 20 *z'''* mating with the upwardly projecting flange *x*.

The beveled faces *z* and *z''* are provided on the valves or cups for the purpose specified, to wit, generating an axial component 25 of the centrifugal force for facilitating the lifting of the valves.

k and *k'* are discharge passages at the upper end of the bowls *b* and *c*, respectively, *t* is a stationary tube inserted coaxially and 30 with some clearance within the hollow shaft *a*, *j* is a central partition in the tube *t* by which it is subdivided into two semi-circular areas, *l* is an inclined deflector arranged at the level of the central plane of the upper 35 bowl *b* at one side of the central partition *j*, the wall of the tube *t* being partly cut away at *o* above the deflector, and *n* is an annulus inserted in the hollow shaft *a* and surrounding the tube *t*. The annulus *n* comprises two faces flaring toward the tube *t* 40 from either side of perforations *p* in the hollow shaft *a*. *q* is a recess formed in the bosses of the parts *d*, *e* adjacent the perforations *p*, and *r*, *r'* are pipes extending downwardly into the part *e* from the recess *q*. Similar means indicated by the same letters 45 but indexed *l'* etc., are provided for the lower part *d'* of the lower bowl *c*.

In operation, and assuming, that the slide 50 *g* has been moved upwards so as to close the upper bowl *b* by its cup or valve *g'*, the shaft *a* is rotated at high speed by any suitable means, not shown, liquid being supplied to the bowls *b*, *c*, and any other bowls on the same 55 shaft. The relative axial displacement of the flanges *y* and *i* and the flanges *y'* and *x* with respect to their recesses is so determined as to provide a certain clearance or to prevent direct engagement of the parts, the solids in 60 the liquid serving as the packing. This packing action occurs immediately upon the bowls being charged with liquid or upon their beginning to rotate, and is absolutely reliable. When the closed bowls are rotating and are 65 continuously supplied with liquid the body

of accumulated solids builds up gradually higher and higher on the bottom of the parts *e* and *d'*, and the liquid is gradually dispelled toward the upper and central regions of the bowls on account of its lower density, 70 and finally is discharged at *k*, *k'*.

Practically, the liquid has been completely separated from the solids when the body of solids has approximately risen to the level of the discharge passages *k*, *k'*. At this moment, the slide *g* is reversed so that its cup or valve *g''* closes the lower bowl *c* and its cup or valve *g'* opens the upper bowl *b*, laying open its slot *f* so that the solids are completely ejected and the bowl is ready for a fresh 80 charge when, in turn, the lower bowl *c* has completed its operation, and the slide *g* is again reversed.

Although it is possible to get a packing between the recesses *h* and *h'*, respectively, of 85 the bowls and the flanges *y* and *y'*, respectively, by the solids of the liquids alone, it may be desirable to have an additional packing. And I prefer to provide for this purpose certain packing means inserted into the 90 recesses *h* and *h'*, respectively, as indicated in the drawing by *h''*.

Any suitable means (not shown) can be provided for automatically regulating the flow of liquids in time with the reversing of 95 the slide *g* so that liquid is only supplied to that bowl or to those bowls which has, or have, been closed by the valve or valves *g'* and *g*.

It is to be understood that I am not limited to the construction shown and described by 100 way of example. For instance I do not desire to be limited to any definite configuration of the bowl or bowls, of their annular slots *f* or *f'* and the slide *g*, an important feature 105 of my invention being that the slide *g* is adapted to close the bowl or bowls and to pack the clearance between the recesses and the flanges cooperating therewith, by the separated solids.

I wish it to be understood that I do not 110 desire to be limited to the exact details of construction shown and described for obvious modifications will occur to a person skilled in the art.

I claim:—

1. In an apparatus of the centrifugal type, a bowl in two sections which define between them a substantially lenticular annular chamber having a peripheral discharge slot of fixed width, and an axially displaceable annular slide adapted to substantially close said slot; the said bowl sections being provided with annular flanges and recesses adapted to cooperate with corresponding recesses and flanges on said displaceable slide, whereby 120 upon closure of said discharge slot by said displaceable slide the solids tend to accumulate between the said flanges and recesses to prevent the discharge of material through 125 said slot.

115

120

125

130

2. In an apparatus of the centrifugal type, a bowl in two sections which define between them an annular chamber having a peripheral discharge slot of fixed width; one of the edges of said discharge slot being flanged outwardly and the other edge being provided with a peripheral recess, an axially displaceable annular slide provided with an annular recess and a peripheral flange; the said recess and said peripheral flange of said slide being adapted to engage, respectively, said flange and said peripheral recess of said bowl sections with a slight clearance; whereby on operation of the device the said discharge slot becomes closed by solids which collect in said clearance.

3. The apparatus of claim 2 wherein the said slide is provided with an annular beveled face between said annular recess and said peripheral flange, the bevel being at such an angle that an axial component of the centrifugal force is generated which tends to open said discharge slot.

4. An apparatus as described in claim 2 in which two bowls are mounted in tandem on the same shaft with the said slide mounted as a sleeve between them, operating to close the discharge slot of one of said bowls as it opens the discharge slot of the second of said bowls.

5. The apparatus of claim 1 wherein auxiliary packing means is provided within the said peripheral recesses to close the space between said flanges and said recesses.

35 In testimony whereof I affix my signature.

ERNST KNÜTTEL.
